Specification for Design.

Patented Oct. 12, 1915.

Application filed June 23, 1915. Serial No. 35,978. Term of patent 14 years.

To all whom it may concern:

Be it known that we, NORMAN J. MOONEY and FRANK MOONEY, citizens of the United States, residing at San Francisco, in the county of San Francisco, State of California, have invented a new, original, and ornamental Design for a Rubber-Tire Tread, of which the following is a specification, reference being had to the accompanying drawing, forming part thereof.

In the drawing, Figure 1 is an edge view of a tire showing a portion of the tread ornamented, Fig. 2 is a section of a tire having the tread ornamented in accordance with this invention, and Fig. 3 is a perspective

view of a portion of a tire having the tread ornamented in accordance with this invention.

What we claim is:

The ornamental design for a rubber tire tread as shown.

In testimony whereof, we have hereunto set our hands this 17th day of June, 1915, in the presence of the two subscribed witnesses.

NORMAN J. MOONEY.
FRANK MOONEY.
